Formica et al., U.S. Appl. No. 29/596,703, filed Mar. 10, 2017 for "Pressurized Air Delivery Console".

(Continued)

Primary Examiner — Lilyana Bekic*(74) Attorney, Agent, or Firm* — Nixon & Vanderhye P.C.**(57) CLAIM**

The ornamental design for a pressurized air delivery console, as shown and described.

DESCRIPTION

FIG. 1 is a front perspective view of a pressurized air delivery console showing our new ornamental design; FIG. 2 is a left side view thereof;

FIG. 3 is a top view thereof;

FIG. 4 is a bottom view thereof; and,

FIG. 5 is a front view thereof.

The broken lines illustrate portions of the pressurized air delivery console that form no part of the claimed design.
